UNITED STATES PATENT OFFICE

CHARLES L'ENFANT, OF NEW YORK, N. Y.

ASSEMBLING DEVICE

Application filed June 17, 1927. Serial No. 199,622.

This invention relates to assembling devices, and has for its primary object and purpose to provide a simple and easily operated means for assembling the component parts of card holding leaves or inserts for card cases of that type wherein each leaf is provided with a card receiving pocket having walls or windows of celluloid or other transparent material.

10 It is an important object of my invention to provide means whereby the celluloid window forming material may be positioned in accurately assembled relation to a marginal binding strip of flexible material and the celluloid sheet connected with said binding strip under the application of heat and pressure with the marginal edge portions of the flexible binding strip projecting uniformly beyond the edges of the celluloid sheet.

20 It is also another object of the invention to provide improved means for subsequently turning the projecting edge portions of the strip of flexible binding material inwardly upon the edges of the celluloid and securely uniting the same therewith under the application of heat and pressure.

It is also an additional object of the invention to provide an improved method of assembling and permanently connecting the parts forming one of the leaves or inserts for such card cases having two card receiving pockets provided with transparent side walls and which involves a minimum number of simple and easily executed operations 30 so that the production of the leaf or insert will require a minimum length of time while absolute uniformity in the product is obtained.

With the above and other objects in view, 40 the invention consists in the improved assembling device and method and in the form, construction and relative arrangement of the several parts of said device as will be herein- 45 after more fully described, illustrated in the accompanying drawing, and subsequently incorporated in the subjoined claims.

In the drawing, wherein I have shown one 50 simple and satisfactory embodiment of the invention, and in which similar reference

characters designate corresponding parts throughout the several views,—

Figure 1 is a plan view illustrating a part of the assembling apparatus, and showing several component elements of the card case 55 leaf or insert arranged in position thereon;

Fig. 2 is a sectional view taken substantially on the line 2—2 of Fig. 1;

Fig. 3 is a plan view of the other part of the assembling apparatus for performing the 60 final step of the assembling method;

Fig. 4 is a transverse section thereof taken on the line 4—4 of Fig. 3;

Fig. 5 is a detail fragmentary plan view of the device shown in Fig. 3, with the presser 65 plates in their lowered positions, and

Fig. 6 is a detail plan view of the final product.

Referring in detail to the drawings, and for the present more particularly to Figs. 70 1 and 2 thereof 5 designates a base of suitable dimensions, preferably of cast metal which is provided in its upper surface with a cavity or depression 6 of rectangular form having raised outer edge portions forming 75 the rabbets indicated at 7 extending in parallel relation to the side and end edges of said base. The surface of the cavity or depression 6 at its approximate center is also formed with spaced transversely extending 80 raised portions or ribs 8.

A presser plate 9 is employed in conjunction with the base 5 and may be operated by any convenient means, said presser head having a maximum length and width equal 85 to the length and width of the depression 6 in the base at the inner sides of the rabbets 7, the bottom face of the presser head having a narrow marginal rib or shoulder 10 substantially equal in thickness to the depth 90 of the depression 6 below the upper surface of the rabbet 7. Said presser head is also centrally provided with the relatively wide transversely extending rib 11 having a width equal to the distance between the spaced ribs 95 8 on the base.

The card holding leaf or insert consists of a single sheet of celluloid or similar flexible transparent material of proper size which is suitably cut and folded upon itself to pro- 100

vide opposed sections indicated at 12 which remain integrally connected with each other along one of their longitudinal edges, one of said sections being centrally provided with a 5 transversely extending slot 13 therein which is of uniform width while the other section is centrally provided with a wider slot having centrally curved portions indicated at 14 which are designed to facilitate entrance to 10 the pockets formed between the opposed sections of the celluloid sheet.

A strip of linen or other flexible material 15 is first arranged upon the base 5 in the space between the ribs 8 thereon. The folded sheet of celluloid is then arranged in place 15 and fits snugly in the depression or cavity 6 within the rabbet 7, and with the lower section of the sheet of celluloid at opposite sides of the slot 13 therein extending over and upon 20 the flexible strip 15. A rectangular binder strip 16 also of flexible material similar to the strip 15 is then arranged in position, said binder strip seating upon the surfaces of the rabbets 7 and being of sufficient width to project inwardly therefrom and over the marginal edges of the upper section of the celluloid sheet. The opposite longitudinal portions of this binder strip are integrally connected with each other by the central transversely 25 extending web 17 of substantially the same width as the strip 15 and overlying the lower section of the celluloid sheet at opposite edges of the slot 13 therein and between the opposed edges of the slot in the upper section of said 30 celluloid sheet. The presser head 9 is then brought downwardly under pressure upon the inwardly projecting portion of the flexible binder strip 16 and upon the web 17 thereof, the ribs 10 and 11 of said presser 40 head firmly pressing the binder strip upon the celluloid sheet and also pressing the lower section of the celluloid sheet at opposite edges of the slot 13 upon the fabric strip 15. By any suitable means, the presser head 9 may be 45 heated, or the base 5 may be heated to the required temperature so as to soften the celluloid sheet or render the same sufficiently plastic so that the fabric material will securely adhere thereto.

50 After the celluloid and the fabric parts have thus been adhesively connected with each other so that the celluloid sheet will be retained in definite relation to the edges of the binder strip 16, said parts are then removed from the base 5 and reversed in position so that the fabric strip 15 is uppermost 55 and then placed upon the metal base member 18. To the opposite side and the end edges of this base member, the presser plates 19 are 60 hingedly connected as at 19', said hinges being located adjacent the upper surface of the base and in parallel relation therewith. The presser plates are preferably provided with suitable finger pieces 20 insulated therefrom 65 whereby said plates may be moved from the

normal position seen in Fig. 4 of the drawings wherein they extend vertically above the base inwardly and downwardly to a horizontal position in parallel relation to the base. When the connected celluloid and fabric parts are arranged upon the base 18, the marginal edges of the fabric binder strips which project beyond the celluloid are turned upwardly against the inner faces of the plates 19 and therefore, when these presser plates are 70 moved downwardly to the horizontal positions, said edges of the fabric binder strips are folded inwardly and downwardly upon the celluloid and also over the ends of the transverse fabric strip 15. The base 18 and the plates 19 are also suitably heated so as to cause the inwardly folded marginal edges of the binder strips to securely adhere to the 75 celluloid.

The connected parts are then removed from 80 the base 18 and by means of a sewing machine, a line of stitching is run around the marginal edges, permanently securing the parts of the binder strip 16 on opposite sides of the celluloid to said celluloid sheets. Also 85 similar lines of stitching may connect the fabric strip 15 adjacent its opposite edges to one section of the celluloid sheet at opposite edges of the slot 13 therein. In this manner, it will be apparent that the leaves or inserts 90 each having two pockets with transparent side walls may be easily and quickly made. Such inserts are adapted to be secured in any desired number within an outer cover or 95 holder, the fabric strips 15 and 17 of the several leaves being centrally stitched to said 100 cover or holder.

From the foregoing description considered in connection with the accompanying drawings, it will be seen that I have devised a 105 method and means for insuring the accurate and uniform production of such card holding devices, and in view of the simple nature of the apparatus required, it will be apparent that these operations can be executed at nominal cost and without requiring expert skill 110 upon the part of the workman.

I have herein shown and described an embodiment of the apparatus which I have found to be entirely satisfactory in practical 115 use. Nevertheless, it is to be understood that my new method and device for assembling the several parts of inserts for card cases, are susceptible of more or less modification in the form, construction and relative arrangement of the several parts thereof, and I therefore, reserve the privilege of incorporating the essential features thereof in all such alternative mechanical structures as may be fairly embodied within the spirit and scope 120 of the invention as claimed.

I claim:

1. Assembling apparatus of the character described comprising a base member having a rectangular cavity in its upper surface to 130

receive a celluloid sheet and provided with a continuous rabbet surrounding said depression to receive a rectangular fabric binder strip adapted to extend from said rabbet over the edges of the celluloid sheet, and a presser head having a marginal rib to engage the inwardly extending portion of the binder strip and fit within said rabbet and adapted to adhesively unite said portion of the binder strip under the application of heat and pressure to the celluloid sheet and with the remaining part of said binder strip projecting uniformly from the edges of the celluloid sheet.

2. In assembling apparatus of the character described, a base having a rectangular depression in its upper surface and provided centrally thereof with spaced transversely extending ribs and having a continuous rabbet surrounding said depression, the space between said ribs adapted to receive a strip of fabric material, and said depression adapted to receive a folded sheet of celluloid with one part thereof extending upon said fabric strip, and said rabbets providing seats for the outer edge portion of a rectangular strip of fabric binding material adapted to be arranged in superposed relation to the celluloid sheet and having a central transverse web connecting the side portions thereof positioned in the vertical plane of said fabric strip, and a presser plate having a continuous marginal rib and a central transversely extending rib, the latter adapted to engage upon said web and the marginal rib to engage the inwardly projecting portion of the rectangular fabric strip and force said parts under heat and pressure upon the celluloid whereby the several fabric parts are adapted to adhere to the celluloid sheet to thereby connect the same with the rectangular binder strip uniformly projecting beyond the edges of the celluloid.

3. In an assembling apparatus of the character described, a base having a continuous rectangular supporting shoulder on its upper surface to receive the outer edge of a rectangular binder frame of flexible material having a central transverse web, the other edge of said frame projecting inwardly from the shoulder and overlying a celluloid sheet positioned on said base, said base being further provided on its upper surface with spaced transversely extending ribs between which a fabric strip is adapted to be positioned, the transverse web of the fabric binder frame overlying the celluloid sheet and said fabric strip, and a presser plate having marginal portions to engage the inwardly projecting portions of the rectangular binder frame and provided with a central transversely extending rib to engage upon said web and by the simultaneous application of heat and pressure to cause the several fabric parts to adhere to the celluloid sheet and

thereby connect the same with the rectangular binder frame uniformly projecting beyond the edges of the celluloid.

In testimony that I claim the foregoing as my invention, I have signed my name hereto. ⁷⁰
